UNITED STATES PATENT OFFICE.

WILLIAM M. GRAFTON, OF SEWICKLEY, PENNSYLVANIA.

RAILWAY SEMAPHORE-SIGNAL.

SPECIFICATION forming part of Letters Patent No. 431,888, dated July 8, 1890.

Application filed January 31, 1890. Serial No. 338,717. (No model.)

To all whom it may concern:

Be it known that I, WILLIAM M. GRAFTON, a citizen of the United States, residing at Sewickley, in the county of Allegheny and State of Pennsylvania, have invented certain new and useful Improvements in Railway Semaphore-Signals; and I do hereby declare the following to be a full, clear, and exact description of the invention, reference being had to the accompanying drawings, which form part of this specification.

This invention has relation to railway semaphore-signals, and has for its object to provide a signal in which the swinging blade or arm, indicating by its positions "danger," "caution," and "safety," shall be clearly and fully visible at all times and at any position. Ordinarily the swinging blade or arm of the signal is pivotally supported on the post by a bolt, shaft, or spindle which intersects or coincides with a line drawn through the center of the blade in the direction of its length and passes directly through the post. The blade in swinging upon this center necessarily maintains a radial position or relation, and hence when dropped to a vertical line is coincident with the post, and therefore either entirely hidden or rendered indistinguishable. Uncertainty and confusion arise from this cause, as an engineer not perceiving the signal-arm itself clearly and distinctly cannot be positive the line is clear or distinguish between the actual condition and the negative indication resulting from the accidental displacement of the blade, as when torn off by storms or other causes. Absolute safety in signaling requires that the blade shall be clearly visible in any and all of its three positions.

The accidental removal of a signal-blade from the post or from the casting is not uncommon, and where engineers are accustomed to reading "clear" when the arm indicates neither "danger" nor "caution," and do not look for the arm itself, very serious results are likely to occur. It is obvious that the indication "line clear" or "safety" should be as positive as the indications "caution" or "danger."

My invention accordingly consists in providing as a means for the support and pivotal arrangement of the signal blade or arm

an elbow-lever or bell-crank, which is preferably cast in one piece with the counterpoise-weight, and also with the spectacle-rings for the night-signal glasses, and such other appurtenances as may be appropriate or expedient. The essential feature of my invention is, however, the elbow-lever or bell-crank, pivotally attached by a bolt passing through the end of one arm and through the signal-post and carrying on the end of the other arm, at a right angle with the first, the signal arm or blade. With this arrangement the pivoted arm of the bell-crank is always in a radial position with reference to the pivotal center, while the signal-blade is always tangential to the circle described by the pivotal arm, and as the latter is long enough to project beyond the side of the post when in a horizontal position the blade, being then vertical, will hang entirely outside and clear of the post, where it can be directly seen. The pivotal arm will also project beyond the post when the blade stands at the half-way position of "caution," and hence in this position the blade is entirely exposed to view, while with the ordinary arrangement the blade is partly hidden.

In the accompanying drawings, illustrating a semaphore-signal embodying my invention, Figures 1, 2, and 3 are front elevations showing the signal-blade in its three positions, respectively.

A designates the signal-post, surmounted by the lantern B and having bolted to its upper part the plate C, through which passes the pivotal bolt D.

E is the signal blade or arm, and F the bell-crank or elbow casting, which is usually cast or provided with the supplementary arm G, carrying the counterpoise-weight H, and with the spectacle-rings I K. The parts referred to may be in one or more pieces, and the spectacle-rings may be attached to the weight H, or located otherwise, as may be deemed expedient.

The drawings show a double signal—that is, a post carrying two blades (front and back) projecting in opposite directions. Both blades are arranged in the same way, and hence a description of one is sufficient.

The blade E is of the usual or any appropriate construction, and is fitted and bolted

into a socket *e*, cast in the end of the arm *f*, which for the purpose of distinction may be termed the "tangential" arm of the bell-crank *F*.

5 The relation of the blade to the post is clearly indicated in the different views, Fig. 3 showing the blade in its vertical position, wherein it is seen to be perfectly and entirely free from the post and as clearly distinguishable as when in the horizontal or danger position.

Any desired number of blades may of course be hung on the one post to indicate with reference to different tracks, sidings, &c.

15 Having described my invention, what I claim as new, and desire to secure by Letters Patent, is—

1. In a railway semaphore-signal, the combination, with the signal-post, of the elbow-

lever or bell-crank pivotally attached to the 20 post and supporting the signal blade or arm in a tangential position or at a right angle with the pivotal arm of said lever, substantially as described.

2. In a railway semaphore-signal, the signal-blade-supporting casting, consisting of a bell-crank or elbow-lever, one arm of which supports the signal-blade, while the other is pivoted at its extremity to the signal-post, and a supplementary arm supporting a counterpoise-weight, substantially as described.

In testimony that I claim the foregoing I have hereunto set my hand this 23d day of January, 1890.

WILLIAM M. GRAFTON.
